IRON HOLDER

Stanley Y. Shepard, Sr., Atherton, Calif.

Application September 15, 1947, Serial No. 773,952

2 Claims. (Cl. 248—117.1)

1

The invention, in general, relates to means for supporting or suspending articles in spaced relationship to a work table or the like for preventing damage to such work table through accidental misuse of the article or inadvertent maintenance thereof in a heated condition on or adjacent to the work table. More particularly, the invention relates to an improved laundry iron holder affording effective support for a hot iron with no likelihood of accidental dislodgement of the iron from the holder or tipping of the holder itself.

As is perhaps well known, a number of different types of laundry iron holders have heretofore been developed and marketed for household use. Many of these prior iron holders are somewhat expensively constructed with unusually heavy bases to obviate overturning of the iron while hot, and other types of these previously constructed iron holders have involved complex assemblies with an undue number of parts and consequent high production costs, but with little aid or features of advantage to the housewife for enabling quick or simple attachment and detachment in operative position on a board. The present invention is directed to the provision of an iron holder which obviates the disadvantages and expensive costs of these prior laundry iron holders.

A primary object of the present invention is to provide an improved laundry iron holder which is of appreciably lightweight construction for ready handling by the average housewife; which can be inexpensively produced; and which is highly efficacious in its functional characteristics to hold an iron in a non-hazardous, spaced relationship with respect to an ironing board.

Another important object of the invention is to provide an improved iron holder of the indicated nature which is additionally characterized by the provision therein of a unique spring clamp for rigidly yet detachably securing the holder in operative position to a work table or ironing board.

A still further object of my invention is to provide a laundry iron holder of the aforementioned character which includes resilient clamping ears for firmly grasping the iron at the sides to prevent lateral movement thereof and permitting, in conjunction with the spring handle clamp, the carrying of the iron with and on the holder from place to place at will.

Other objects of the invention, together with some of the advantageous features thereof, will appear from the following description of a pre-

ferred embodiment of the invention which I have illustrated in the accompanying drawings. It is to be understood that I am not to be limited to the precise embodiment shown, nor to the precise arrangement of the various parts thereof, as my invention, as defined in the appended claims, can be embodied in a plurality and variety of forms.

Referring to the drawings:

Fig. 1 is a perspective view of a preferred embodiment of the invention in operative position attached to a work table or ironing board.

Fig. 2 is a side elevational view of the preferred embodiment of the invention with laundry iron thereon, and with the embodiment in operative position clamped to an ironing board.

Fig. 3 is a side elevational view, in reduced size, of the preferred embodiment of my invention indicating the manner of suspending the same from a wall bracket, either with or without the iron contained therein.

Fig. 4 is a front elevational and inverted view of the preferred embodiment of the invention suspended from a wall bracket.

Fig. 5 is a perspective view of the improved handle spring clamp forming a part of the preferred embodiment of the present invention.

Fig. 6 is a development of the main body portion of the preferred embodiment of the invention.

Fig. 7 is a development of the spring handle clamp.

In its preferred form, the improved laundry iron holder of my invention preferably comprises a substantially continuous sheet defining a base and an upper plate; said base having a guide thereon and said upper plate having upstanding ears on opposite sides thereof, together with a spring handle clamp slidably retained in said guide.

As particularly illustrated in Figs. 1 and 6 of the annexed drawings, the body portion of my improved laundry iron holder preferably is stamped from a continuous sheet 11 which may be relatively thin section steel or aluminum or other relatively light-weight metal. Or, if desired, the main body portion of the holder can be molded from a suitable plastic material, such as "Tenite" or any phenolic or urea condensate. As shown, the sheet 11 is turned upon itself and formed so as

to provide a base 12 and an upper plate 13 with the base disposed substantially horizontal and the upper plate 13 inclined with respect to the horizontal so that the tip end thereof is slightly lower than the rear thereof. The sheet 11 is so cut and stamped as to afford a relatively wide portion 14

on upper plate 13 at the rear thereof which tapers to a relatively narrow and pointed tip 16. Moreover, the sides of the upper plate 13 are serrated and upturned so as to provide a pair of upstanding ears 17 and 18 on each side of the upper plate in opposed pairs for resiliently gripping the sides 19 of an iron 20 when seated on the upper plate 13, all as indicated in Fig. 2 of the drawings, which shows the nose 21 of the iron fitted between opposing front ears 17 of the upper plate and the front tip of the iron overlying the front tip 16 of the upper plate. The material of which the main body portion of the holder is formed conveniently is struck out to afford reinforcing ribs 22 on the surface of the upper plate as well as reinforcing ribs 23 on the rear of base 12 and reinforcing ribs 24 on the front portion of the base. As shown, the base 12 is bent upon itself to afford front and rear upstanding sections merging with a flat, substantially horizontal portion 25. Moreover, the front upstanding section of the base is further bent upon itself to provide a projection 26 for securing the base 12 and plate 13 rigidly together either by means of welding or by other extraneous fasteners, not shown.

In accordance with my invention, the horizontal extending portion 25 of the base 12 is cut out and struck up to provide a handle clamp guide 31 consisting of two opposed strips 32 and 33 disposed substantially normal to the horizontal portion 25 of the base. Each of the strips 32 and 33 is formed with an elongated slot 34 therein for slidably receiving in the strips a guide retaining pin 36 carried by a spring handle clamp 37 which is depicted in perspective view in Fig. 5 and in development, without the pin 36, in Fig. 7 of the drawings. As shown in Fig. 5, the spring handle clamp 37 is partially turned upon itself to afford a straight portion 38 and a double-curved portion 39 and provide a finger-loop 40 by which the holder can be carried about when the spring handle clamp has been fitted into the guide 31 in operative position, as indicated in Figs. 1, 2, 3 and 4. The loop 40 of the spring handle clamp 37 serves to receive the end 41 of a work table or ironing board 42, see Figs. 1 and 2, with the double-curved portion 39 of the clamp underlying the board 42 and resiliently bearing against the same to clamp the holder to the work table or board. It should be observed that the front portion of the base 12 is cut away, as indicated at 43, Fig. 6, to permit passing of the clamp 37 therethrough when assembling the same in the guide 31. The opening 43 is sufficiently wide to permit the clamp 37 to be pushed inwardly toward the front of the holder and, in this forwardly pushed position, the holder can be stored away in a relatively small space on a closet shelf. On the other hand, the holder may be suspended by means of the handle clamp 37 on a suitable bracket 44 fastened to a wall 45, see Fig. 3 and Fig. 4 and such suspension bracket can be strong enough to suspend not only the holder itself but the holder and laundry iron contained thereon. The handle clamp 37 is sufficiently strong and is so positively attached to the guide 31 that the iron

holder containing the laundry iron can be picked up and carried about readily by the housewife. Moreover, to insure that the handle clamp does not become dislodged from the guide 31, I preferably form the retaining pin 36 with enlarged or ball ends 46 thereon.

The improved laundry iron holder of my present invention is of inexpensive construction since it can be stamped and formed from thin section, 10 relatively light-weight metal or molded from a relatively inexpensive plastic material. The holder has a minimum of parts but is of such rigid and compact construction that it can be handled readily by the average housewife and moved about 15 with an iron thereon with ease. Moreover, the inwardly bent, resilient ears formed on the upper plate for retaining the iron prevents dislodgement of the iron. Further, the rigidity of the clamping action between the spring handle clamp 37 and the work table or ironing board prevents tipping 20 of the holder and the iron so that there is little likelihood of damage resulting from handling the iron.

It also is to be observed that when an iron is 25 disposed on the holder, the base of the iron does not rest directly on the upper plate due to the presence of the reinforcing ribs 22 which hold the iron in spaced relationship to the plate, as indicated in Fig. 2, thus affording an air flow between 30 the iron and the base preventing undue heating thereof with a hot iron on the holder.

I claim:

1. An iron holder comprising a base, an upper plate supported above and in spaced relationship to said base, a guide on said base comprising a pair of spaced elongated strips disposed normally to said base; each of said strips having an elongated slot therein, and a spring handle clamp slidably retained in said slots of said guide; said 35 clamp being adapted to be removably fitted to an ironing board or the like for rigidly fastening the holder thereto.

2. An iron holder comprising a base, an upper plate supported in spaced relationship to said 40 base, a guide on said base comprising a pair of spaced elongated strips disposed normally to said base; each of said strips having an elongated slot therein, a spring handle clamp consisting of a loop portion for receiving the end of a work table 45 or ironing board and a slotted straight portion, and a retaining pin disposed transversely of said clamp and extending through the slot of the straight portion thereof as well as through the elongated slots of said strips to effect slidable 50 mounting of said clamp on the holder.
